LIPSTICK DEVICE

James L. Younghusband, Chicago, Ill.

Application May 27, 1942, Serial No. 444,756

6 Claims. (Cl. 206—56)

My invention relates to a device for holding lipstick, said device so constructed as to make the lipstick available for application by the user.

Among the objects of my invention is to create a simplified construction for the projection and retraction of a lipstick with relation to a case. To provide a construction which upon removal of the closure will automatically project a lipstick so that the same may be applied by the user free from any obstructing mechanism adjacent the projected lipstick and which will also retain the lipstick holder within the case and such other objects, advantages and capabilities as will later more fully appear and which are inherently possessed by my invention.

While I have shown in the accompanying drawings preferred embodiments of my invention, yet I wish it understood that the same are susceptible of modification and change without departing from the spirit of my invention.

Referring to the drawings, Figs. 1 and 2 are sectional elevational views of my lipstick device having stop means within the case, in open and closed positions respectively, and Figs. 3 and 4 are sectional elevational views of details thereof; Figs. 5 and 8 are sectional elevational views of my lipstick device having a second cord acting as a stop in open and closed positions respectively and Figs. 6 and 7 are sectional elevational views of details thereof; Figs. 9 and 10 are sectional elevational views of my lipstick device with the cord looped through the holder, in open and closed positions respectively and Fig. 11 is an elevational view of a detail thereof partly in section; and Figs. 12 and 13 are elevational sectional views of my lipstick device having an elastic cord, in open and closed positions respectively.

The embodiment selected to illustrate my invention comprises a hollow body member 10 or case having side walls 11, a bottom 12 and an open top 13. A spring 14 is positioned within said body member 10, with the bottom portion of the spring 14 engaging the interior of the closed bottom 12. The upper portion of said spring 14 engages the bottom of a holder or cup 15. The cup 15 is slightly smaller in its dimensions than the hollow interior of the body member 10, so as to permit vertical movement with respect thereto. Said cup 15 is adapted to hold a lipstick 16 or the like.

A cap or closure 17 for the open top 13 is provided, said cap adapted to be removably positioned by friction grip within depression 18 on the side walls 11 adjacent their upper ends.

A connector such as a cord, chain or other length of material 19 is attached at or adjacent to one end to said cup 15 and extends downwardly through spring 14 and opening 20 in body 10 preferably in bottom 12, thence to cap 17 to which it is attached at or adjacent its other end.

In my preferred form cord 19 has a knot 21 positioned in cup 15 and of a larger size than opening 22 in cup 15 through which cord 19 below knot 21 passes. Cord 19 may also have a knot 32 positioned in cap 17 beyond opening 23 therein.

When the device is in closed position, with caps 17 covering the open top 13, cord 19 extends horizontally across the balance of the cap 17 to one of the side walls 11 and then vertically along said side walls to the outside of bottom 12 where it extends horizontally until it enters opening 20 thence vertically to cup 15.

In use after the user removes cap 17 from open top 13 spring 14 exerts upward pressure on the bottom of cup 15 and projects lipstick 16 above the open top 13 as shown in Fig. 1.

In order to retain cup 15 in case 10 and prevent it from being ejected by spring 14 or from falling out when the case is inverted with the cap removed, I provide stop means positioned inside the case to engage the cup 15.

One embodiment of my stop means as shown in Fig. 1 is to provide inner walls 11 with an inwardly extending shoulder 40 adjacent their upper portion. This shoulder extends within the interior of the case 10 to such an extent that when the cup 15 is moved sufficiently upwardly it contacts the shoulder 40 and is stopped from further upward movement, and is thus retained within case 10. Shoulder 40 may be integrally formed with walls 11, or suitably attached thereto. In assembling this construction, bottom 12 would be suitably attached to case 10 after the holder and spring had been placed in the case. Instead of shoulder 40 I may provide stop means in the form of a collar 41 which is attached to walls 11 at open top 13 as shown in Fig. 3 said collar 41 extending down along the inside of walls 11 to be engaged by the holder on its upward movement to prevent passage of the holder thereby and to retain the holder in the case. My stop means as shown in Fig. 4 is a pin 42 extending inwardly from one of the walls 11 within the upper portion of case 10 and positioned to engage cup 15 and retain it in case 10.

In another embodiment of my invention, stop

means is provided in the form of a secondary connector or cord 44, the upper end of which is attached by knot 45 or other suitable means to holder 15. The lower end of the cord 44 is suitably attached to or bears against the bottom 12 of the case 10. For example, the lower end of cord 44 may have knot 46 attached to the inside of bottom 12 by a staple 47 or the like. Cord 44 may also have a ball or end member 48 attached to its lower end, said ball being attached by a staple 47 to the inside of bottom 12, or the lower end of cord 44 may extend through a small opening 49 in bottom 12 or side wall 11, with the ball 48 on the exterior of the case 10; said ball 48 being of larger diameter than opening 49 cannot pass therethrough and bears against the outside of case 10. Said connector 44 is of such a length that it will retain the holder 15 within case 10.

In another embodiment, my connector 19 is suitably attached on one end to cap 17, extends upwardly through opening 20 in case 10, continues upwardly through opening 50 in the bottom 51 of holder 15, extends laterally to opening 52 in the bottom of holder 15 and then downwardly through said opening 52 to the bottom 12 of case 10. The end of cord 19 has a knot 53 attached by staple 54 or the like to the inside portion of bottom 12. Cord 19 is of sufficient length so that it permits cap 17 to be placed over open top 13. Cord 19 is also of sufficient length so that upon removal of cap 17 from open top 13, and upon spring 14 forcing holder 15 upwardly that cap 17 will engage the bottom 12 of case 10 and cord 19 will retain holder 15 within case 10. A cover 59 is placed over the inside of bottom 51 of holder 15 so as to receive the lipstick 16, and protect connector 19 from contact with the lipstick 16. Cord 19 instead of being attached to the inner portion of bottom member 12 may extend through an opening 55 in recessed portion 53 in bottom 12 and have a knot or other suitable end portion or member 57 formed therewith or attached thereto, said end member being of larger size than opening 55 so as not to pass therethrough.

In another embodiment of my invention I provide a connector 58 of elastic material such as rubber, extending between and attached on opposite ends to the holder 15 and closure 17. The connector 58 is adapted to stretch to permit closure 17 to be moved to close the open top 13. When the closure is removed, connector 58 contracts and spring 14 pushes holder 15 with its lipstick 16 upwardly for use. In this open position closure 17 bears against bottom 12 and connector 58 is of such a length and of sufficient strength to so resist the expanding force of spring 14 as to retain the holder 15 in the case 10 and prevent its ejection therefrom.

Having thus described my invention, I claim:

1. In a lipstick device having a case with side walls, a bottom and an open top, a holder slideable in said case and adapted to carry lipstick, a closure for the open top of said case, a spring in said case below said holder for moving the holder upwardly to project the lipstick above the open top for use, and a connector attached to said closure and said holder and adapted when said closure is moved to closed position on said open top to pull said holder and its lipstick within said case against said spring, and a secondary connector attached to said holder and engaging the bottom of said case, said connector of such length as to retain the holder in said case.

2. In a lipstick device having a case with side walls, a bottom and an open top, a holder slideable in said case and adapted to carry lipstick, a closure for the open top of said case, a spring in said case below said holder for moving the holder upwardly to project the lipstick above the open top for use, and a connector attached to said closure and said holder, said connector being of elastic material and adapted to stretch to permit said closure to be moved to closed position on said open top and to pull said holder and its lipstick within said case against said spring, said connector adapted to contract upon the closure being removed from the open top so that said closure contacts the bottom of the case, said connector in contracted position of sufficient length and strength resistant to said spring to retain said holder within said case and prevent its ejection therefrom.

3. A lipstick device comprising a hollow body member having side walls, a bottom, an open top and an opening adjacent its lower portion, a holder adapted to hold lipstick movable within said body member, a spring positioned within said body member with its lower portion contacting said bottom and its upper portion contacting the bottom of said holder, a separate closure adapted to removably close said open top, a flexible member attached on one of its ends to said closure, extending through said opening in said body member and continuing upwardly to said holder, said spring adapted to exert upward pressure on said holder for projecting said lipstick above said open top when said closure is removed, said closure adapted upon removal from said open top to fall by gravity away from said open top so that the user may grasp the side walls of the body member free from any obstruction by said closure for application of said lipstick by the user, said flexible member adapted upon pressure from the user on said closure to pull said holder with its lipstick against the action of said spring back into said hollow body member, and stop means extending within said body member for preventing said holder from passing out said open top of said body member.

4. A lipstick device comprising a hollow body member having side walls, a bottom, an open top and an opening adjacent its lower portion, a holder adapted to hold lipstick movable within said body member, said holder having a pair of spaced openings, a spring positioned within said body member with its lower portion contacting said bottom and its upper portion contacting the bottom of said holder, a separate closure adapted to removably close said open top and a flexible member attached on one of its ends to said closure, extending through said opening in said body member, continuing upwardly through one of said spaced openings in said holder, extending laterally to and through the other of the spaced openings in said holder and then downwardly to the bottom of said body member with its other end attached to said bottom, said spring adapted to exert upward pressure on said holder for projecting said lipstick above said open top when said closure is removed, said closure adapted upon removal from said open top to fall by gravity away from said open top so that the user may grasp the side walls of the body member free from any obstruction by said closure for application of said lipstick by the user, said flexible member of such a length as to retain the holder within the body member, said flexible member adapted upon pressure from the user on said closure

sure to pull said holder with its lipstick against the action of said spring back into said hollow body member.

5. A lipstick device comprising a hollow body member having side walls, a bottom having a pair of openings therethrough and an open top, a holder adapted to hold lipstick movable within said body member, said holder having a pair of spaced openings, a spring positioned within said body member with its lower portion contacting said bottom and its upper portion contacting the bottom of said holder, a separate closure adapted to removably close said open top and a flexible member attached on one of its ends to said closure, extending through one of said openings in said bottom, continuing upwardly through one of said spaced openings in said holder, extending laterally to and through the other of the spaced openings in said holder and then downwardly to the bottom of said body member with its other end extending through the other of said openings in said bottom, and means on the other end of said flexible member of larger size than said last mentioned opening in said bottom said means bearing against the outer portion of said bottom, said spring adapted to exert upward pressure on said holder for projecting said lipstick above said open top when said closure is removed, said closure adapted upon removal from said open top to fall by gravity away from said open top so that the user may grasp the side walls of the body member free from any obstruction by said closure for application of said lipstick by the user, said flexible member of such a length as to retain the holder within the body member, said flexible member adapted upon pressure from the user on said closure to pull said holder with its lipstick

against the action of said spring back into said hollow body member.

6. A lipstick device comprising a hollow body member having side walls, a bottom, an open top and an opening adjacent its lower portion, a holder movable within said body member, said holder having a pair of spaced openings in its lower portion, a cover positioned above the openings in said holder, said cover adapted to hold lipstick, a spring positioned within said body member with its lower portion contacting said bottom and its upper portion contacting the bottom of said holder, a separate closure adapted to removably close said open top and a flexible member attached on one of its ends to said closure, extending through said opening in said body member, continuing upwardly through one of said spaced openings in said holder, extending laterally to and through the other of the spaced openings in said holder and then downwardly to the bottom of said body member with its other end attached to said bottom, said spring adapted to exert upward pressure on said holder for projecting said lipstick above said open top when said closure is removed, said closure adapted upon removal from said open top to fall by gravity away from said open top so that the user may grasp the side walls of the body member free from any obstruction by said closure for application of said lipstick by the user, said flexible member of such a length as to retain the holder within the body member, said flexible member adapted upon pressure from the user on said closure to pull said holder with its lipstick against the action of said spring back into said hollow body member.

JAMES L. YOUNGHUSBAND.
